(57) **CLAIM**

The ornamental design for a piezomotor connector, substantially as shown and described.

DESCRIPTION

FIG. 1 is a top, right side perspective view of a piezomotor connector, showing our new design;

FIG. 2 is a bottom, right side perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines shown represent unclaimed subject matter and form no part of the claimed design.

1 Claim, 4 Drawing Sheets
